FACE GUARD FOR A HELMET

Dennis L. Burns, 4044-A NE. 109th St.,
Seattle, Wash. 98125

Filed Feb. 5, 1973, Ser. No. 329,467

Term of patent 14 years

Int. Cl. D2—03

U.S. Cl. D2—233

Fig. 3.

FIG. 1 is a front elevational view of a face guard for a helmet showing my new design;

FIG. 2 is a side elevational view thereof; and,

FIG. 3 is a top plan view.

I claim:

The ornamental design for a face guard for a helmet, as shown.
